UNITED STATES PATENT OFFICE.

AUGUST PHILIPPS AND OSWALD PHILIPPS, OF FRANKFORT-ON-THE-MAIN, GERMANY.

AUTOMATIC PLAYING MECHANISM FOR MUSICAL INSTRUMENTS WORKING WITH A PLURALITY OF RECORDS.

1,115,735.

Specification of Letters Patent.

Patented Nov. 3, 1914.

Application filed January 6, 1913. Serial No. 740,533.

To all whom it may concern:

Be it known that we, AUGUST PHILIPPS and OSWALD PHILIPPS, subjects of the German Emperor, and residents of Frankfort 5 on-the-Main, Germany, have invented certain new and useful Improvements in Automatic Playing Mechanism for Musical Instruments Working with a Plurality of Records, of which the following is a full, 10 clear, and exact description.

This invention relates to musical instruments operated by mechanism which is controlled by playing records such as perforated sheets or music rolls. The invention 15 is applicable to such instruments wherein a plurality of perforated records are used, for causing to be played simultaneously by separate records a melody and its accompaniment, the two parts of a duet, 20 and so forth. In such cases it is essential to provide means for controlling the speed of movement of the respective records in order to secure proper synchronism in the playing.

It is the object of the present invention to provide a simple apparatus whereby the movement of the records may be synchronized in an automatic manner.

A further object is to provide pneumatic 30 apparatus whereby the supply of the working fluid to the respective motors which actuate the respective records may be controlled for the purpose of securing synchronism.

These objects are attained according to the present invention by providing the records with a series of small holes at definite intervals, and arranging that these holes shall move over corresponding openings in 40 the tracker bars or the like in playing from the records. The openings in the tracker bars or the like communicate with pneumatic apparatus by means of which for instance, when one record falls behind the

other in its movement, more working fluid is supplied to the motor which drives the retarded record until it again overtakes the other record. The pneumatic apparatus need not necessarily effect the control by 45 this particular method, but it might effect it for instance by throttling the supply of fluid to the motor of the advanced record, or otherwise checking its movement.

The invention is shown diagrammatically 50 by way of example, in the accompanying drawing, in an arrangement wherein two

perforated tune sheets are used, driven by pneumatic motors of a known type.

In the drawings the two perforated tune sheets are marked I and II, the take up rolls 60 of the respective tune sheets being driven by pneumatic motors marked k and k^1 .

The note sheets I and II are formed with holes a and a^1 in corresponding positions and at regular intervals apart, and the apertures in the tracker bars b and b^1 over which these holes pass, are connected by pipes c c^1 to the pneumatic controlling device. This comprises a wind chest e , in which a pair of valve members d , d^1 are arranged. The 70 pipes, c , c^1 open in recesses in the wind chest e below membranes or bellows at the bottom of the valve stems, while the valve heads work in chambers g , g^1 at the other end. These chambers are normally open to the 75 atmosphere through the openings at f , f^1 . Whenever either of the valves d or d^1 is raised owing to the pressure of air from below, its head closes the opening f or f^1 and exposes the opening connecting the 80 chamber g or g^1 with the wind chest e . The valve d is shown as being raised in this way. Pipes h , h^1 lead from the chambers g , g^1 to the bellows i , i^1 of the controlling mechanism. In the example illustrated, this mechanism controls the flow of air to or from the wind motors k and k^1 through the pipes l and l^1 , a slide valve m , and a pipe n . This air supply is in addition to the main supply by which the motors k and k^1 are driven. 85 Either of the motors which receives auxiliary wind in this way for a short time, will quicken its movements slightly owing to the extra wind. Hence the corresponding tune sheet will move on more quickly in 90 order to bring it into synchronism with the other tune sheet. The bellows i and i^1 are connected by rods to the slide valve m so that this valve will be moved toward one side or other if one or other of the bellows 100 is collapsed while the other is free to expand. As the holes a , a^1 are continually passing over the apertures of the respective tracker bars b , b^1 , the valves d , d^1 are normally actuated simultaneously, when the 105 slide m is held central under the equal opposed actions of the two bellows i and i^1 .

Assuming that the apparatus is to operate with air suction, the working thereof is as follows. The tune sheet II is indicated as 110 having fallen slightly behind the tune sheet I, and a hole a of the latter is over the cor-

responding aperture of the tracker bar b , while the corresponding hole a^1 of the tune sheet II has not yet reached its tracker bar aperture. Hence atmospheric air can enter 5 through hole a and pipe c and press up the membrane of the valve d , as the air in the sheet e is exhausted. The chamber g consequently has its opening f closed, and air is drawn out of the bellows i through the 10 pipe h , chamber g and the chest e . The bellows i will consequently collapse while the air has free access to the bellows i^1 , so that the slide m is at once moved toward the right as shown, connecting the pipe l^1 of the 15 motor k^1 with the auxiliary wind pipe n , while the pipe l is closed. Hence the motor k^1 is accelerated by the auxiliary air as is required, until the holes a a^1 of the two tune 20 sheets come simultaneously over their tracker bar aperture, when the forces tending to move the slide m equalize or counteract one another and it assumes a mid position.

We claim:—

- 25 1. In an automatic playing mechanism for musical instruments, in combination with a plurality of synchronically moving note sheets, having perforations and the motors therefor, a recessed wind chest, valve members within said chest provided with membranes at one end and with valve heads at the opposite end, tracker bars for said note sheets, and pipes connecting said tracker bars with the recess of said wind chest below 30 said membranes, chambers for said valve heads normally communicating with the atmosphere, a controlling device having a slide valve, means for connecting said con-

trolling device with said wind chest for the operation of said slide valve upon the closing of one of said chambers against the atmosphere, and means connected to said slide valve for supplying auxiliary air to the motor for the lagging sheet for increasing its speed in order to synchronize the movements of both sheets. 40

2. In an automatic playing mechanism for musical instruments, in combination with a plurality of synchronically moving note sheets having perforations and the motors therefor, a recessed wind chest, valve members within said chest provided with membranes on one end and valve heads on the opposite end, tracker bars for said note sheets, and pipes connecting said tracker bars with the recess of said wind chest, below said membranes, chambers for said valve heads, normally communicating with the atmosphere, a controlling device having a slide valve, bellows and pipes connecting said controlling device with said wind chest for the alternate operation of said slide valve upon the closing of the corresponding chamber against the atmosphere, and an air supply pipe connected to said slide valve 50 for supplying auxiliary air to the motor of the lagging sheet and for increasing its speed in order to synchronize the movements of said note sheets. 55

In testimony whereof we affix our signatures in presence of two witnesses.

AUGUST PHILIPPS.
OSWALD PHILIPPS.
